CLAIM

The ornamental design for an electric grinder base, as shown and described.

DESCRIPTION

FIG. 1 is a front, top perspective view of an electric grinder base, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of the electric grinder base, shown in an environment of use; and,

FIG. 10 is a rear, bottom perspective view thereof.

The broken lines are shown for the purpose of illustrating both parts of the electric grinder base as well as environmental subject matter. None of the broken lines form part of the claimed design.

1 Claim, 10 Drawing Sheets
